(57) **CLAIM**

The ornamental design for a portable defibrillator carrier, as shown and described.

DESCRIPTION

FIG. 1 is a rear, right, top perspective view of a first embodiment of a portable defibrillator carrier.

FIG. 2 is a rear view of the portable defibrillator carrier of FIG. 1.

FIG. 3 is a front inside view of the portable defibrillator carrier of FIG. 1.

FIG. 4 is a front view of the portable defibrillator of FIG. 1 illustrating an operating environment thereof.

FIG. 5 is a rear, right, top perspective view of a second embodiment of a portable defibrillator carrier.

FIG. 6 is a rear view of the portable defibrillator carrier of FIG. 5.

FIG. 7 is a front inside view of the portable defibrillator carrier of FIG. 5; and,

FIG. 8 is a front view of the portable defibrillator of FIG. 5 illustrating an operating environment thereof.

The broken lines represent portions of the portable defibrillator carrier that form no part of the claimed design. The broken lines form no part of the claimed design.
